UNITED STATES PATENT OFFICE.

EDGAR O. BLEKRE, OF SIOUX CITY, IOWA.

DESIGN FOR AN ELASTIC-TIRE TREAD.

56,267.

Specification for Design.

Patented Sept. 14, 1920

Application filed March 26, 1920. Serial No. 369,090. Term of patent 14 years.

To all whom it may concern:

Be it known that I, EDGAR O. BLEKRE, a citizen of the United States, and a resident of Sioux City, in the county of Woodbury and State of Iowa, have invented a new, original, and ornamental Design for Elastic-Tire Treads, of which the following is a specification, reference being had to the accompanying drawing, forming a part thereof.

Referring now to the illustrations, Figur 1 is a fragmentary plan of an elastic vehicl tire embodying my ornamental design; an

Fig. 2 is a transverse section thereo taken on the line 2—2 of Fig. 1.

I claim:

The ornamental design for an elastic tir tread as shown.

EDGAR O. BLEKRE.
